UNITED STATES PATENT OFFICE

134,293

DESIGN FOR A COMBINED INK BOTTLE STOPPER AND QUILL

Augustine M. Mazzarelli, New York, N. Y., assignor to Plastic Quill and Novelty Corporation, New York, N. Y., a corporation of New York

Application July 19, 1941, Serial No. 102,397

Term of patent 7 years

To all whom it may concern:

Be it known that I, Augustine M. Mazzarelli, a citizen of the United States, residing at New York, in the county of New York and State of New York, have invented a new, original, and ornamental Design for a Combined Ink Bottle Stopper and Quill, of which the following is a specification, reference being had to the accompanying drawing, forming part thereof.

bined ink bottle stopper and quill, showing my new design.

The dominant features of my design reside in the portions shown in full lines.

I claim:

The ornamental design for a combined ink bottle stopper and quill, as shown and described.

AUGUSTINE M. MAZZARELLI.
